DENTAL FLOSS DISPENSER

Irvin J. Gershen, Springfield, N.J., assignor to Johnson & Johnson, a corporation of New Jersey

Filed July 27, 1960, Ser. No. 61,537

Term of patent 14 years

(Cl. D52—2)

Fig. 1 is a perspective view of a dental floss dispenser showing my new design;

Fig. 2 is a front elevational view;

Fig. 3 is a right side view of Fig. 2;

Fig. 4 is a rear view; and

Fig. 5 is a top view.

The undisclosed side of the dental floss dispenser is substantially the same in appearance as the side shown.

I claim:

The ornamental design for a dental floss dispenser, as shown and described.
